UNITED STATES PATENT OFFICE.

CHARLES C. MAXWELL, OF WATERTOWN, SOUTH DAKOTA.

LAND-PRESSER.

SPECIFICATION forming part of Letters Patent No. 517,352, dated March 27, 1894.

Application filed June 22, 1893. Serial No. 478,536. (No model.)

To all whom it may concern:

Be it known that I, CHARLES C. MAXWELL, a citizen of the United States, residing at Watertown, in the county of Codington and State 5 of South Dakota, have invented certain new and useful Improvements in Land-Pressers; and I do declare the following to be a full, clear, and exact description of the invention, such as will enable others skilled in the art to 10 which it appertains to make and use the same.

This invention has relation to an improvement in land pressers, and it has for its prime object to provide a machine with tapering lugs arranged upon rollers, and also tapering, 15 circular flanges arranged thereon, which will press and pack the loose soil on the surface so as to produce corresponding depressions in the earth instead of pulverizing the top as has heretofore been done with land rollers.

20 Other objects and advantages will appear from the following description and claims when taken in connection with the annexed drawings, in which—

Figure 1, is a rear elevation of my improved 25 machine. Fig. 2, is a vertical, transverse, sectional view, taken in the plane indicated by the dotted line x, x , on Fig. 1. Fig. 3, is a sectional, detail view of one of the rollers, with my improvements applied. Fig. 4, illustrates in perspective and partly broken away 30 two sections of the circular flanges. Fig. 5, is a cross sectional view of one of the strips of a roller, illustrating a modification of the pegs or lugs. Fig. 6, is a perspective view of 35 one of the strips, bearing a series of pegs, and Fig. 7, is a perspective view of one of the scrapers.

Referring by letter to said drawings: A, indicates a frame, which may be of a general, 40 rectangular form in outline, and is provided with a suitable seat a , and a draft tongue b . The style of frame may be varied as it forms no part of my invention. Depending from this frame are suitable hangers B, in which 45 is journaled a transverse shaft C, as shown.

As a convenient embodiment of my invention, I have illustrated two rollers although it is obvious that more or less may be employed. These rollers may comprise a ring 50 or head D, at opposite ends having a hub c , in which the shaft C, is received, and said shaft may be secured to the heads by a key

or other suitable fastening devices. These heads have a circumferential flange d , and an inwardly directed lateral flange e .

E, indicates longitudinal strips of board or other suitable material which are secured at opposite ends by bolts f , and nuts or other fastening devices to the inwardly directed flanges e of the head. 55

F, indicates the pegs or lugs, which are designed to project from the outer surface or periphery of the rollers. These pegs or lugs are preferably of a truncated cone shape in outline, and in making them of metal, for the 60 sake of lightness and cheapness, I would form them hollow, as better shown in Figs. 2, and 3, of the drawings, while in making them of wood or similar material, I would form them solid, as shown in Fig. 5, of the drawings. 65 These pegs may be cast and a number of them formed entire, with perforated flanges g , at their bases so that they may be secured upon the strips E, by nails h , screws, or the like. The circumferential flanges D, of the heads, 70 are designed to extend from the base of the rollers, a distance corresponding with or approximately the same as the pegs F, and these flanges may also taper from their bases, outwardly, (see Fig. 3,) so that when drawn over 75 the ground or earth, they may form creases of a corresponding shape.

H, indicates circular flanges. These flanges which are made hollow for the sake of lightness, are also formed with flanges i , at their 80 bases, by which they are secured upon the surface of the rollers. I have illustrated one of these flanges arranged between every four sets of pegs or lugs F, although it is obvious that they may be arranged farther apart or 85 nearer together as desired, although a machine of the construction illustrated, has been found to give good results. In order that these flanges, which taper as described, may be readily placed upon the roller and removed 90 when desired, I prefer to form them in sections, and I provide the end of one section with a groove or recess k , and the contiguous end of another section with a tongue or tenon l , to enter said groove or recess in the opposite section. 95

In using wooden pegs, I provide them with a tenon m , and provide the strips E, with holes n , to receive said tenon, although it is 100

obvious that other means might be employed for securing the pegs upon the rollers.

I, indicates a longitudinal bar, which is arranged in rear of the rollers and is held in position by brackets K, which are secured to the hangers B, as shown. I provide this bar with scrapers L, which are of a form substantially as shown in Fig. 7, of the drawings, and may comprise a strip of steel or other suitable material, bent at p, so as to form a scraping edge q, which is designed to assume a position adjacent to the surface of the roller, between the pegs and flanges thereon so as to thoroughly remove any dirt or mud which may adhere to the roller surface during operation. These scrapers have an angular bend r, at their opposite ends to receive the inner and under side of the bar I, and the angular portions are perforated as at s, to receive a bolt or screw.

With a device of the character described, I am enabled to pack and press the loose soil so as to produce hard pressed creases, and holes or depressions, without pulverizing the top, and these creases and holes will catch fine loose dirt, which might otherwise be blown away from the roots of grain, and by such provisions, I can retain the moisture much longer after rain, which is due to the fact that the earth being packed, will absorb and hold the moisture, much better than if rolled solid upon the top or left loose.

Having described my invention, what I claim is—

35 1. A land press having a revoluble roller,

armed with tapering pegs or lugs arranged at intervals in circular series, and also having tapering, annular flanges arranged at suitable intervals between the circular series of pegs, substantially as specified.

2. A land press having a revoluble roller armed with tapering pegs or lugs arranged at intervals in circular series and also having tapering, annular flanges arranged at suitable intervals between the circular series of pegs, and heads having annular flanges of a corresponding shape, and provided with journal apertures to receive a shaft, substantially as specified.

3. The combination with a roller; of hollow, tapering pegs or lugs arranged in circular series, and hollow, tapering flanges intercepting the said pegs, substantially as specified.

4. In a land press, the combination with a suitable frame; of the rollers journaled in hangers depending from said frame, a longitudinal bar supported on brackets extending from the hangers, the scrapers of a form, substantially as shown, and secured to the bar, the tapering pegs secured to the surface of the roller in circular series, and the intercepting circular flanges also secured to the surface of the roller, substantially as specified.

In testimony whereof I affix my signature in presence of two witnesses.

CHARLES C. MAXWELL.
